COMBINED TIE AND GARMENT RACK

Arthur S. Wynne, Sr., 1368 Wrenwood,
Memphis, Tenn. 38103

Filed July 22, 1971, Ser. No. 165,441

Term of patent 14 years

Int. Cl. D6—06

U.S. Cl. D6—116

FIG. 1

FIG. 3

FIG. 1 is a top plan view of a combined tie and garment rack showing my new design, the bottom being essentially the same as the top shown;

FIG. 2 is an elevational view taken from one side thereof, the opposite side being a mirror image of the side shown; and

FIG. 3 is a front elevational view thereof.

I claim:

The ornamental design for a combined tie and garment rack, as shown and described.
